UNITED STATES PATENT OFFICE

HERBERT G. WHITEHOUSE, OF NEWARK, NEW JERSEY, ASSIGNOR TO THE RIKER COMPANY, A CORPORATION OF NEW JERSEY

DESIGN FOR A SHOE BUCKLE

Application filed July 17, 1931. Serial No. 40,581. Term of patent 7 years.

To all whom it may concern:

Be it known that I, HERBERT G. WHITEHOUSE, a citizen of the United States, residing at Newark, in the county of Essex and State of New Jersey, have invented a new, original, and ornamental Design for a Shoe Buckle, of which the following is a specification, reference being had to the accompanying drawings, forming part thereof.

In said drawings, Fig. 1 is a front face view, and Fig. 2 is a top edge view of a shoe buckle, showing my new design.

I claim:—

The ornamental design for a shoe buckle, as shown.

HERBERT G. WHITEHOUSE.
